UNITED STATES PATENT OFFICE.

RUFUS WRIGHT, OF CHICAGO, ILLINOIS.

COMBINED LATCH AND CHECK.

SPECIFICATION forming part of Letters Patent No. 534,707, dated February 26, 1895.

Original application filed January 8, 1894, Serial No. 496,099. Divided and this application filed January 8, 1894. Serial No. 496,100. (No model.)

To all whom it may concern:

Be it known that I, RUFUS WRIGHT, a citizen of the United States, residing at Chicago, in the county of Cook and State of Illinois, 5 have invented a certain new and useful Combined Latch and Check for Doors and the Like, of which the following is a specification.

This application is filed as a division of my application, Serial No. 496,099, for Letters 10 Patent of the United States, filed of even date herewith. My said application, Serial No. 496,099, embodies several forms or arrangements of combined latch and check, adapted to normally or ordinarily oppose the closing 15 of a door with a yielding spring resistance of sufficient strength to act as a check against undue slamming of the door, and also adapted to permit the catch or latch to be relieved at will from the normal spring resistance 20 opposed to its retraction when it is forced back by the act of closing the door, whereby, when the door is closed and latched and it is desired to unlatch and open the same, the latch can be relieved from said normal spring 25 resistance and hence can be manually retracted with ease.

For the purpose of this application I have elected to specially claim herein the arrangement or construction involving a spring resistance 30 which normally opposes the retraction of the latch so as to provide a check for preventing undue slamming of a door or the like, and a movable abutment normally and temporarily interposed between the 35 spring resistance and the latch, so that while the abutment is thus interposed between the latch and spring resistance, the retraction of the latch will be opposed by the latter, while on the other hand, by freeing the movable 40 abutment from engagement with the latch, the latter will be entirely relieved from such spring resistance and hence can be manually retracted with great ease. To such end therefore I provide in conjunction with the latch, 45 and a spring resistance preferably consisting of a yielding spring cushion, a movable abutment subject to the spring and adapted to interlock with the latch, whereby by unlocking said device the latch can be retracted independently of the same.

In the accompanying drawings,—Figure 1

represents a section taken longitudinally through the casing, and illustrates in elevation, an arrangement whereby the latch can be entirely relieved from the spring resistance 55 of an elastic air-cushion. Fig. 2 is a face or plan view of the same with the cover or face-plate removed. Fig. 3 is a view similar to Fig. 1, showing the latch relieved from the spring resistance. Fig. 4 illustrates the latch or 60 catch removed. Fig. 5 illustrates the movable abutment which can be interposed between the latch and spring resistance and normally interlocked with or placed subject to the retraction of the latch. Figs. 6, 7 and 65 8 respectively correspond with Figs. 1, 2, and 3, the devices being similar in principle but involving slight changes in detail, as herein-after explained. Fig. 9 shows the swinging latch of Figs. 6, 7 and 8. Fig. 10 represents 70 in perspective the key for disengaging the movable abutment from the latch, and for retracting the latch when the movable abutment is disengaged therefrom. Fig. 11 shows in perspective the latch, the elastic air-cush- 75 ion, the movable abutment, and the key, the forward end of the movable abutment being raised by the key from engagement with the latch. Fig. 12 is a similar view showing the latch partially retracted by the key. 80

Referring first to Figs. 1 to 5, inclusive, the latch A, normally retracts against a spring resistance or an elastic air-cushion B through the intervention of a movable abutment C, arranged to normally provide a rear extension for the latch. The rear end c of this movable abutment temporary latch extension abuts against the elastic air-cushion B, and the latter is simply provided with a constantly open pin-hole or minute vent b. This movable abutment C is separate from the latch, and has its forward portion arranged within a slot a, in the latch. The slot a is formed with a shoulder a', and the movable abutment is provided with a shoulder c' (Figs. 4 and 5). Said shoulders of the latch and movable abutment are normally or usually in engagement with one another, so that when the latch is moved back by the act of closing the door, the latch will in effect be retracted against 90 the full or normal resistance of the elastic air-cushion. In order to relieve the latch from 95 100

such resistance, so that it can be easily retracted, the movable abutment C can be raised so as to free it from positive engagement with the latch, it being seen that the slot in the 5 latch is of sufficient width to admit of such movement on the part of movable abutment C, and that when the forward portion of the latter is thus raised, its shoulder c' will be freed from shoulder a' in the latch-slot, and 10 thereby allow the latch to be retracted independently of the movable abutment C. During said operation, the portion of the movable abutment C within the latch-slot will simply rest upon the forward inclined bottom wall 15 a^2 of said slot, so that while the abutment C remains passive, the latch will be moving back, and while thus operating will be relieved from the spring resistance normally opposing its retraction. After thus retracting the latch, 20 and opening the door, the latch can be moved forward either manually or by any desired arrangement of light spring arranged independently of the spring cushion A. For example, 25 a key comprising a spindle E having a ward e , can be used for unlocking the movable abutment C from the latch and for both retracting and projecting the latch while it is thus relieved from the resistance of cushion A. With such arrangement, the ward e on the spindle 30 can be arranged for operation between shoulders a^3 , a^4 , on the latch, so that the latter can be operated by the spindle similar to the operation of a latch by the ward of an ordinary key. The ward e of the spindle can also 35 be employed for unlocking movable abutment C from the latch, and to such end, it can be arranged so that when the spindle is turned in one direction, it will come under the forward inclined end portion of the movable 40 abutment C and thus suitably lift the same out of locking engagement with the latch, and then engage shoulder a^4 on the latch so as to retract the latter.

Obviously a coiled spring could be applied 45 to the spindle so as to cause it to normally project the latch, or a light spring could be applied to the latch for such purpose, and since springs for normally projecting latches are so well known and common devices it is 50 not deemed necessary to make special illustration of the same one illustration of a light spring for normally projecting a vibratory latch being shown in succeeding figures. In order to insure positive engagement between 55 the movable abutment C and latch when the latter is projected as in Figs. 1 and 2, a spring F is secured within the casing G and arranged to bear upon said movable abutment. By such arrangement the forward portion of the 60 movable abutment C will be caused to drop and engage or rest in opposition to the stop or shoulder a' of the latch when the latter has been projected as in Fig. 1.

In Figs. 6 to 9, inclusive, the construction 65 shown involves the principles of operation of the construction illustrated by the preceding figures, the principal difference between said

two sets of figures being in details. Thus, in Figs. 6 to 9, inclusive, the latch A' is a swinging latch and to such end is pivoted at a^5 70 within the casing. The slot a^6 of this swinging latch is curved and has a notch a^7 at its rear end. The movable abutment C' has its rear end c arranged to normally act against and compress the elastic air-cushion B, and 75 to such end the forward portion of said movable abutment is forked to embrace the latch and provided with a cross-pin c^2 which is normally within notch a^7 at the rear end of slot a^6 in the latch. By such arrangement the 80 movable abutment C' can be temporarily locked to the latch so that when the latch is forced back by the act of closing the door, it will be opposed by the full or normal resistance of a spring afforded by the elastic air-cushion. In order to relieve the latch from the spring resistance normally opposing its 85 retraction, the key spindle E' has the ward e' formed similar to the ward of key spindle E in preceding figures and arranged to engage under and slightly raise the forward portion of movable abutment C' when the spindle is turned in a direction to retract the latch and thereby lift pin c^2 out of notch a^7 . Further movement of the key spindle in the same direction causes its ward to engage a stop a^8 on the latch and thereby retract the latter independently of the movable abutment C', as in Fig. 8.

From the foregoing it will be seen that during the use of the latch and elastic air-cushion as a check to prevent the slamming of a door or the like, the latch in both arrangements is normally opposed by the full elastic resistance, and that when for example the 105 door is closed and it is desired to open the same, the latch can be entirely relieved from the resistance of spring cushion B by unlocking or disengaging from the latch, the movable abutment normally interposed between 110 the latch and cushion as a temporary portion of the latch.

What I claim as my invention is—

1. A combined latch and check comprising 115 a latch, a spring resistance, a movable abutment normally interposed between the latch and the spring resistance whereby the automatic retraction of the latch shall force the abutment against the spring resistance and thereby cause the latter to oppose such retraction on the part of the latch, said abutment being also adapted and arranged for disengagement from the latch, and means whereby the said abutment may be disengaged from the latch and the latter retracted 120 independently of the movable abutment and without opposition on the part of the spring resistance, substantially as set forth.

2. A combined latch and check comprising 125 a latch, an elastic air-cushion, a movable abutment constituting a power transmitting device normally interposed between the two and arranged for alternate connection with and disconnection from the latch as a power 130

transmitting medium, and a key for temporarily disconnecting said device from the latch, substantially as set forth.

3. A combined latch and check comprising
5 a latch, an elastic air-cushion, a movable
abutment constituting a power transmitting
device normally interposed between the two
and arranged for alternate connection with
and disconnection from the latch, and a key
10 adapted and arranged for both disconnecting
said abutment from the latch and for re-
tracting the latter, when the abutment is
freed therefrom, said latch being provided
with stops between which the ward *e* of the
15 key is arranged, one of said stops being po-
sitioned to be engaged by the said ward when
the key is operated to raise the abutment from
engagement with the latch, and the other stop
being arranged to be engaged by said ward
20 when the key is operated to allow the abut-

ment to drop into position for engaging the
latch, substantially as and for the purpose set
forth.

4. The combination of a slotted latch, an
elastic air-cushion, and an intervening mov-
able device engaging in the slot of the latch,
said slot being adapted at its rear portion to
provide a stop with which the said device can
temporarily engage, substantially as set forth. 25

5. The combination of the latch a compar-
atively light spring resistance constantly op-
posed to its retraction, a stronger spring re-
sistance normally opposing its retraction, and
means for temporarily relieving the latch
from the stronger spring resistance, substan- 30

35 tially as and for the purpose set forth.
